UNITED STATES PATENT OFFICE.

D. AZRO A. BUCK, OF WATERBURY, CONNECTICUT, ASSIGNOR TO HIMSELF AND EDWARD A. LOCKE, OF SAME PLACE.

IMPROVEMENT IN WATCH-DIALS.

Specification forming part of Letters Patent No. **222,658**, dated December 16, 1879; application filed September 26, 1879.

To all whom it may concern:

Be it known that I, D. AZRO A. BUCK, of Waterbury, in the county of New Haven, and in the State of Connecticut, have invented certain new and useful Improvements in Watch-Dials; and I do hereby declare that the following is a full, clear, and exact description thereof, reference being had to the accompanying drawings, making a part of this specification, in which—

Figure 1 is a perspective view of my improved dial in place within a case. Fig. 2 is a like view of the same with the figure-plate removed; and Figs. 3 and 4 are, respectively, cross-sections upon central lines of Figs. 1 and 2.

Letters of like name and kind refer to like parts in each of the figures.

The design of my invention is to enable watch-dials to be easily and cheaply secured in place and removed therefrom, and to provide accommodation for the dial-wheels; to which end it consists, principally, in a watch-dial composed of a recessed base and a figure-plate fitted over said recess, and provided between said parts with space for dial-wheels, substantially as and for the purpose hereinafter specified.

It consists, further, in a detachable watch-dial adapted to be secured in place by being fitted within and sprung into a rabbet, which is formed within a case-center or watch-plate, and receives and embraces its edge, substantially as and for the purpose hereinafter shown.

In the annexed drawings, A represents a circular metal plate provided with a raised edge, a , within which is formed a rabbet, a' , that is either square or slightly undercut. Fitted within the rabbet a' is a plate, B, which corresponds to and closely fills the same, and is held in place by the spring of the metal.

The outer plate, B, is held at such distance from the recessed outer face of the plate A as to furnish between said plates sufficient space to receive the usual dial-wheels and such

wheels as may be required for connecting the hands with stem-setting mechanism, said wheels being pivoted upon said plate A.

The plate B is provided upon its outer face with the usual divisions and signs, and, in connection with the plate A, is to be secured within the case of a watch, and in such position will perform the usual functions of a dial.

To enable the dial-wheels to be exposed it is only necessary that the hands should be taken off, when said plate B may be easily and quickly removed.

If desired, the base-plate A may also be secured in place within the case-center by means of a rabbet formed in the latter, and caused to embrace the edge of said plate, while in case of the employment of a single dial, of usual form, no other fastening is required.

A material saving in expense is effected over the usual method by my method of securing in place a dial, while by the use of the double hollow dial a much better and more convenient arrangement of the dial-wheels is secured.

Having thus fully set forth the nature and merits of my invention, what I claim as new is—

1. A watch-dial composed of a recessed base and a figure-plate fitted over said recess, and provided between said parts with space for dial-wheels, substantially as and for the purpose specified.

2. A detachable watch-dial adapted to be secured in place by being fitted within and sprung into a rabbet formed within a case-center or watch-plate, which receives and embraces its edge, substantially as and for the purpose shown.

In testimony that I claim the foregoing I have hereunto set my hand this 6th day of September, 1879.

D. AZRO A. BUCK.
